UNITED STATES PATENT OFFICE

FRANK CARTLIDGE, OF CHICAGO, ILLINOIS, ASSIGNOR TO SULLIVAN MACHINERY COMPANY, A CORPORATION OF MASSACHUSETTS

MINING MACHINE

Application filed January 28, 1926, Serial No. 84,464. Renewed December 27, 1929.

This invention relates to mining machines, and more particularly to mining machines for undercutting coal.

In mining a vein of coal it is customary to undercut the same to a desired depth and then blast down or otherwise free the coal for loading. Blasting is the usual practice. When the undercutting is performed by the ordinary room and pillar machine or long-wall machine having a cutter bar which cuts a kerf of a vertical dimension of perhaps six inches, the free room between the bottom of the kerf and the bottom of the block of coal that is to be removed is insufficient for best results and an unduly large percentage of the coal is reduced to powdered form too fine for desirable use. In hand mining what is known as a snubbing cut was commonly made and the mouth of this cut being considerably 20 deeper than the depth of the kerf at the deepest point from the face, smaller powder charges could be used and the falling coal fractured and rolled out in a much better manner than with an ordinary comparatively 25 vertically shallow kerf. Various efforts have been made to effect the formation of such cuts by machine, but the cutting process reduces to dust all the coal actually cut by the bits and the percentage of fines or slack has accordingly run very high.

In my copending application, Serial No. 580,907, I have disclosed a loop bar type machine for making a cut of this general description and the present invention is an improvement thereover and is designed to permit the formation of a snubbing cut with the production of less fine coal.

Among the objects of the present invention is the provision of an improved mining machine adapted to form a snubbing cut with a minimum of fines. Another object of the invention is the provision of an improved mining machine having a pivoted cutter bar of novel form and improved swinging mechanism therefor. A further object of the invention is to provide improved feed operating and cutting mechanism operating gearing. A still further object of my invention is to provide an improved mechanism adapted for both room and pillar and longwall cut-

ting. Other objects of the invention will subsequently appear.

Another cutting mechanism operating gearing. A still further object of my invention is to provide an improved mechanism adapted for both room and pillar and longwall cutting. Other objects of the invention will subsequently appear.

With these objects in view, one feature of the invention involves the provision of a plurality of angularly disposed cutter bars so designed and arranged that two comparatively narrow slots or grooves are formed in the coal and converge from the breast of the coal toward a junction point which may be spaced somewhat from the rear extremity of the block to be broken down. The formation of converging cuts in this manner provides, depending upon the relationship of the cutter bars, anything between a V-shaped opening or recess and an opening having a forward V-shaped portion but a rearward parallel sided, comparatively narrow portion.

A further and more specific feature of the invention consists in the arrangement of a plurality of cutter bars whose cutting portions are respectively, at least in part, angularly inclined to each other and each of which carries circulating cutting elements, while the actuating devices for the cutting elements, specifically the cutter chain driving sprockets, are disposed on aligned axes and actuate them together. This last feature involves the employment of at least one bent bar and the use thereon of a universal chain.

A still further feature consists in the arrangement of feed operating and controlling members and bar swinging means in an improved manner permitting the same mechanism to serve both as feed operating and bar swinging means. Still further features of the invention and advantages thereof will be apparent from the following specification.

The invention may obviously be practiced in longwall as well as room and pillar machines and a mechanism adapted for both operations is disclosed. A feed chain type of feed or a plural cable type of feed may either one be employed as desired, but only the latter is specifically illustrated.

In the accompanying drawings in which two forms of the invention is shown for purposes of illustration,

Fig. 1 is a plan view of a mining machine constructed in accordance with the illustrative embodiment of the invention.

Fig. 2 is a side elevation thereof.

Fig. 3 is a vertical longitudinal section on the line 3—3 of Fig. 1 showing the front end 10 of the machine.

Fig. 4 is a vertical transverse section on the line 4—4 of Figs. 1 and 3.

Fig. 5 is a vertical transverse section on the line 5—5 of Figs. 1 and 3.

Fig. 6 is a horizontal section on the line 6—6 of Fig. 2, parts being omitted.

Fig. 7 is a detailed section on the line 7—7 of Fig. 2.

Fig. 8 is a similar section showing a modification.

Figs. 9, 10 and 11 are partially diagrammatic views showing respectively in plan, in side elevation, and looking forward, portions of the bar swinging mechanism proper.

Fig. 12 is a fragmentary detail of a cutter chain.

Figs. 13, 14 and 15 are diagrammatic views showing the machine in use, Fig. 13 showing the positioning of the machine preparatory to starting a cut, Fig. 14 a stage in room and pillar cutting and Fig. 15 the machine cutting longwall.

In its illustrative embodiment the invention comprises a bottom plate 1 upon which a motor 2 is suitably mounted on framing 1^a. The motor provides power for actuating cutting mechanism generally designated 3, for swinging said cutting mechanism through mechanism generally designated 4, and for effecting feed of the machine transversely of a face by mechanism generally designated 5. During transverse feed the angle of the machine is controlled through mechanism generally designated 6. The motor 2 is of a well known reversible type.

The motor 2 is provided with an armature shaft 10 which carries at its forward end a spur pinion 11 which meshes with and drives a spur gear 12 rotating on a horizontal axis 50 above and in the same vertical plane with the axis of rotation of the armature shaft 10. The pinion 11 is keyed as at 13 upon a longitudinally extending horizontal shaft 14. The shaft 14 is journaled in bearings 15 and 16 in the forward frame of the machine which is generally designated 17. At its forward end the shaft 14 carries a bevel pinion 18 keyed as at 19 to the shaft and constituting a driving element for the cutting mechanism 3.

The pinion 18 meshes with a comparatively large bevel gear 21 rotating upon a vertical axis and journaled upon a vertically extending stud member 22. The gear 21 is housed 65 in a chamber 23 at the front end of the frame

17 and a division wall 24 at the bottom of this chamber has a depending cylindrical portion 25 surrounded by a bearing 26 which forms a journal for the upper end of a casting 27 which supports the cutting mechanism. The casting 27 at its lower end has an arm 28 provided with a bearing 29 surrounding a sleeve 30 upon the lower end of the stud 22. Adjustably secured to a forwardly projecting portion 32 formed upon the casting 27 at its lower end is a cutter bar 33 about whose periphery a cutter chain 34 having cutting elements 35 circulates. A similarly projecting portion 36 is formed near the upper end of the casting 27 and adjustably secured thereto is a second cutter bar 37 which initially extends horizontally as at 38 for a short distance, then inclines downwardly as at 39 and at its front end extends into juxtaposition with the lower bar 33, a bracket member 40 being bolted to both bars to hold them in juxtaposition. The bar 38 has a cutter chain 42 thereon provided with cutting elements 43 and it will be observed that the kerfs cut by the elements 43 and 35 intersect in such manner that the bracket member 40 has a path cut for it on cutting operation of the bars. The cutter chain 42 is of the universal type and comprises between the cutter bit carrying links intermediate pivoted links 45 having pivots 46 between their ends at right angles to the plane of the other pivots (see Fig. 12). It will be observed that the bracket 40 is longitudinally adjustable due to a slot and bolt connection 47.

The stud shaft 22 is surrounded by a sleeve 48 to whose lower end a cutter chain driving sprocket 49 is keyed at 50. The sprocket 49 drives the cutter chain 34. Adjacent its upper end and slightly below the latter the sleeve 48 carries a cutter chain driving sprocket 52 which rotates in the plane of the plane portion 38 of the cutter bar 37 and drives the cutter chain 42 on the cutter bar 37. The sprocket 52 is keyed at 53 to the sleeve 48 and above the sprocket 52 the sleeve 48 carries an annular clutch member 54 keyed thereto at 55 and having upwardly opening clutch recesses 56 into which clutch pins 57 carried by a vertically reciprocable clutch member 58 may enter. The pins 57 pass through openings 59 near the hub of the gear 21 and serve to connect that gear with the clutch member 54 and so with the sleeve 48 and cutter chain driving sprocket 49 and 52. Vertical movement of the clutch pins 57 is controllable by a pivoted member 60 to whose outer end are pivoted depending shifter elements 61 engaging the clutch member 58, and angular movement of the member 60 is controlled by an eccentric pin 62 engaging in a slot 63 at the opposite end of the member 60 and adjusted by a controlling handle 64.

The cutter bar carrying member 27 is formed at its upper end with a large sheave

65 having a groove 66 in its outer periphery to receive a bar swinging cable. A cam operated locking pin 67 controlled by a handle 68 engages in a recess 69 upon a boss 70 rigidly 57 with the upper cutter bar 38 and locks the cutter bars in longitudinal alignment with the machine frame when such position is attained. A similar cam operated locking pin mechanism 68² is disposed in a position 90° ahead of the locking pin 67 and operates to hold the cutter bar at right angles to the frame 1^a for longwall cutting.

The feeding mechanism 5 is driven from a worm 72 arranged on the shaft 14 midway between the bearings 15 and 16. The worm 72 engages a worm wheel 73 keyed to a sleeve 74 journaled at 75 and 76 in the frame 17 and coaxial with a shaft 77 extending transversely of the machine frame in the same horizontal plane with and in front of the armature shaft 10. The shaft 77 is journaled at the right hand side of the frame looking forward in a bearing 78 in the machine frame and at its opposite end in a thrust bearing 79. The sleeve 74 carries a spur pinion 80 having relatively long teeth 81. The teeth 81 mesh with a relatively large spur gear 82 rigidly mounted on a shaft 83 parallel to the shaft 77. The shaft 83 is suitably journaled at 84, 85 and 86 in the gear housing 17 and has formed thereon a spur driving pinion 87 which meshes with a gear 88 freely rotatable upon the shaft 77. A clutch member 89 has teeth 90 formed at one end thereof adapted to engage the ends of the teeth 81 and at the other end thereof teeth 92 to engage clutch projections 93 upon the hub of the gear 88. The clutch sleeve 89 is splined as at 94 to the shaft 77 and is reciprocable longitudinally of the latter to effect engagement of the teeth 90 or 92 as may be desired. When the teeth 90 engage teeth 81 the shaft 77 is driven directly with the sleeve 74, but when teeth 92 engage the projections 93 shaft 77 is driven by gear 88 through a train including pinion 80, gear 82, pinion 87 and gear 88. The train first mentioned is adapted for machine movement and that last mentioned for machine feeding during cutting.

A feed operating member, herein in the form of a drum 95, is mounted coaxially with a laterally projecting stud 96 secured as at 97 at the right hand side of the machine frame looking forward. The feed operating member 95 is journaled at one end upon a cylindrical portion 98 of a driving gear 99 and at its other end is supported upon a disk like member 100 journaled upon a bearing 101 surrounding the stud 96. A friction clutch 102 serves to connect the hub 103 of the gear 99 with the feed operating member 95 and fingers 104 extend through openings 105 in the disk member 100 to effect frictional engagement of the clutch 102. Fingers 104 are carried by a circular member 106 mounted near the outer end of a transversely extending

clutch shifter rod 107 passing through the stud 96. Member 107 is threaded at its outer end for cooperation with a handwheel 110 which carries at the center thereof a nut 111 cooperating with the threaded extremity of rod 107. A sleeve 106^a is arranged in splined relation to rod 107 between member 106 and nut 111 and transmits the pressure exerted by the nut to member 106. The opposite end of the member 107 is attached to a transversely extending curved member 108 which transmits a longitudinally acting force to the rod 107. The left hand end of the member 108 carries a threaded bolt member 109 and a hand wheel 110^a carries a nut 111^a cooperating with the bolt and engaging the left hand side of the machine frame, looking forward, to permit control of the loading of the clutch 102 from the left hand side of the frame. A pinion 112 rigidly mounted on the shaft 77 meshes with the gear 99 and drives the latter. Obviously the member 95 may be driven at any speed up to the speed of rotation of the shaft 77 by appropriate adjustment of the clutch 102 or may be left stationary when the clutch 102 is not loaded. A flexible feed cable 113 may be connected as at 114 to the drum 95.

The angular position of the machine frame during cutting may be determined in different ways. A simple mechanism for this purpose is shown in Fig. 8 and comprises a tail rope drum 115^a (see Fig. 8) journaled on a bearing 116 upon a laterally extending stud 117. A brake band 118 controlled by a hand lever 119 through suitable screw and nut tensioning mechanism 120 controls rotation of the drum 115^a. The latter is provided with internal ratchet teeth 122 with which a pawl 123 carried by a pawl carrier 124 cooperates. The pawl carrier is journaled upon a projecting central sleeve 125 of the drum and has upon its outer end a polygonal socket 126 for engagement by a suitable long handled wrench bar or other implement whereby the angle of the machine may be altered by the operator as desired, the ratchet mechanism described permitting the application of force in the most advantageous manner. A handle to wind the cable may be similarly used. A cable 127 is wound on drum 115^a.

A preferred form of mechanism for controlling the tail rope is, however, illustrated in detail in Fig. 7 and shown also in the other views of the machine. This mechanism is adapted to enable power to be applied to the tail rope drum. It will be noted that a stud 161 is suitably supported on the side of the machine frame and has journaled thereon a sleeve 162 which carries in rigid relation thereto a gear 163 which meshes with and is driven by gear 99. A drum 115 is journaled on a bearing 164 surrounding the hub portion of gear 163 and on a bearing 130

165 near the outer end of stud shaft 161. The sleeve 162 and the interior of drum 115 each carry in splined relation thereto a series of friction clutch discs, the discs splined to the drum being numbered 166 and those to the sleeve 167. A plate 168 at the outer end of drum 115 is provided with openings 169 through which fingers 170 on a clutch loading member 171 extend. The stud shaft 161 has a reduced threaded extremity 172 and a threaded hand wheel 173 cooperates with this threaded extremity to apply pressure to the member 171. The tail rope 127 is wound on drum 115. By variably loading the friction discs 166 and 167, the tail rope may be permitted to pay out, be maintained practically uniform in free length, or if the friction is loaded sufficiently, it may be drawn in.

20 The machine frame supports a plurality of cable guiding sheaves about which the cables 113 and 127 may be led. At the right hand side of the frame at the rear end of the latter and somewhat above its bottom is an angularly pivoted tail rope guide sheave 129 around which the cable 127 may be led off to a take up member at the receding side of the machine. Adjacent the sheave 129 and below it is a second larger sheave 130 to which the live cable 113 passes first before being led across the rear end of the machine frame. At the opposite side of the frame and at the rear is another guide sheave 131 and a sheave 132 is suitably mounted forward of the motor on the advancing side of the machine frame. The live rope 113 passes across from sheave 130 to sheave 131, forwardly to sheave 132 and around the latter and off to a jack in advance of the machine during cutting across a face. A central sheave 133 is arranged at the rear end of the machine to facilitate handling. A sheave 134 is also provided to permit moving of the feed cable as shown in Fig. 13 when it is desired to position the machine preliminary to the sumping in of the bar. Sheave 132 is dismountable, together with its support when longwall cutting is to be practiced, and it will be noted that all the other sheaves are protected during such cutting by an upturned face engaging flange 1^b on the bottom plate.

55 Power for the actuation of the bar swinging mechanism, generally designated 4, is obtained from a worm 135 keyed to the shaft 77. The worm 135 engages a worm wheel 136 mounted upon a hollow shaft 137 which is journaled in bearings 138 at opposite sides of a chamber 139 in which the worm wheel 136 is located. Beyond the bearings 138 the hollow shaft 137 carries rotatably mounted upper and lower drums 141 and 142, which may be respectively frictionally connected to the shaft by friction clutches 143 and 144 through inner clutch sleeve members 145

and 146 which are respectively keyed to opposite ends of the hollow shaft 137. The upper drum 141 has secured to the friction clutch housing thereof a closure plate 147 into which a threaded sleeve 148 carrying a hand wheel 149 extends. The sleeve 148 is adapted to engage a clutch shipper 150 controlling the loading of the clutch 143 directly and the hub of the hand wheel 149 is engageable with a head 152 on opposite movement. The head 152 is mounted on a shaft 153 extending through the hollow shaft 137 and carrying at its lower end a longitudinally slidably clutch loading member 154 which serves to load the lower clutch 144. Accordingly, opposite adjustment of the hand wheel 149 serves to effect loading respectively of the clutches 143 and 144. A continuous cable 155 extends from the upper drum directly to the sheave 65, around the latter, back over a horizontally journaled transversely disposed sheave 157, rearwardly around an inclined sheave 158 and onto the drum 142. Cable 155 is held by wedge means 159 in rigid relation to the sheave 65 so that tension applied to the cable by the drums 141 and 142 is operative to effect bar swing. Since the ends of the cable 155 extend in like directions around the drums 141 and 142, it will be obvious that upon clutching of either drum to shaft 137 the latter will cause drawing in of its respective portion of cable 155 and so the bar may be oppositely swung.

50 The mode of operation of the mechanism described will be already obvious to those skilled in the art, but certain possible operations may be briefly summarized.

55 By suitable arrangements of the live rope 113 and tail rope 127 and operation of drums 95 and 115, possible at machine moving speed when clutch teeth 90 engage teeth 81, the machine frame may be positioned approximately normal to the working face adjacent the right hand rib (see Fig. 13), the cutter bars 33 and 37 moving back by suitable control of drum 142. Drum 141 may then be caused to draw upon its portion of cable 155 and the bars will make an arcuate sumping cut until a position perpendicular to the face (see Fig. 14) is reached when they will be aligned with the machine frame and may be locked rigid with the latter by locking pin 67. This swinging sumping cut may well be at slow swinging speed, through gars 80, 82, 87, 88, but positioning of the bar may be accomplished faster by connecting teeth 81 and 90 directly. Of course, in soft coal, swinging during cutting may also be at the faster speed. With the bar now rigidly held in alignment with the frame, the machine may be fed across the face as an ordinary room and pillar machine, cable 113 being led around sheaves 130, 131 and 132 off to a jack in advance of the machine, and cable 127 around sheave 129 to a take up at the right

hand rib, feed being controlled by drum 95 and angle by drum 115. At the end of the across-the-face cut the pin 67 may be withdrawn and drum 141 operated to complete the kerf with a swinging cut. For longwall cutting the bar is swung into the coal to the position shown in Fig. 15 and the cable 113 used to effect feed. During this operation the feed drum is controlled by hand wheel 110 at the right hand side of the machine frame, i. e. the side away from the face.

From the foregoing description it will be evident that very desirable results may be accomplished by this mechanism. Relatively narrow kerfs may be cut by the two cutter bars as each lends strength to the other. The block of coal intermediate the kerfs will not be reduced to powder, but will fracture off in sizable lumps. Further, the bottom of the coal to be shot or otherwise broken down will be provided with a projecting longitudinally extending shoulder which will engage the bottom and provide for easier fracturing into lump with less powder charges. Moreover, due to the type of cutting mechanism used less power will be required than with a loop type bar, and less fine coal needs be produced both because narrower kerfs are possible and because the upper chain run can be shorter than the lower chain run.

While I have in this application specifically described two forms which my invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a mining apparatus, a plurality of relatively converging cutter bars provided with relatively movable cutting elements, and direct driving means for said cutting elements rotating on axes in the same straight line.

2. In a mining apparatus, a plurality of converging cutter bars provided with circulating cutter chains, and driving sprockets for said chains rotating on axes parallel to the same straight line, said bars being most widely separated at points adjacent said sprockets.

3. In a mining apparatus, a plurality of converging cutter bars provided with circulating cutter chains, and driving sprockets for said chains rotating on aligned axes, said bars being closest at their ends remote from said sprockets.

4. In a mining apparatus, a plurality of converging cutter bars provided with circulating cutter chains, and driving sprockets for said chains rotating on axes parallel to

the same straight line and perpendicular to the plane of one of said bars, said bars converging from the ends adjacent said sprockets towards their other ends.

5. In a mining apparatus, a plurality of converging cutter bars provided with circulating cutter chains, and driving sprockets for said chains rotating on aligned axes perpendicular to the plane of one of said bars, said bars being most widely separated at points adjacent said sprockets.

6. In a mining apparatus, cutting mechanism including a pair of cutter bars each provided with circulating cutting elements moving in orbits extending longitudinally of the bars and spaced at one end and extending into juxtaposition at their other ends, and means for holding their juxtaposed ends in rigid relation.

7. In a mining apparatus, cutting mechanism including a pair of cutter bars spaced at one end and extending into juxtaposition at their other ends, and means for holding their juxtaposed ends in rigid relation permitting relative adjustment thereof.

8. In a mining apparatus, cutting mechanism including a pair of cutter bars provided with circulating cutting elements and spaced at one end and extending into juxtaposition at their other ends, said bars being operative to cut intersecting kerfs, and means of a dimension to move freely within said intersecting kerfs for holding the juxtaposed ends of said bars in rigid relation.

9. In a mining machine, in combination, a machine frame slidable on its bottom over a mine bottom during cutting and carrying a motor, cutting mechanism, a feed operating member adapted to cooperate directly with flexible feeding means and rotating on a transversely extending axis, a shaft extending longitudinally of the machine and carrying spaced elements constituting feed operating member and cutting mechanism actuating elements, and power transmission mechanism between said elements and said member and mechanism respectively, the former transmission mechanism including plural speed gearing whose elements rotate at all times on parallel stationary axes in advance of said motor.

10. In a mining apparatus, a machine frame slidable on its bottom over the mine bottom during cutting and having at the rear end thereof a motor and wholly at the forward end thereof cutting mechanism, and means for feeding and guiding said machine transversely of a face during cutting including a plurality of independently rotatable feed operating and controlling members each adapted to cooperate directly with flexible feeding means and rotatable on stationary axes on the same side of the machine frame.

11. In a mining apparatus, a machine frame slidable on its bottom over the mine

bottom during cutting and having at the rear end thereof a motor and wholly at the forward end thereof cutting mechanism, and means for feeding and guiding said machine transversely of a face during cutting including a plurality of independently rotatable feed operating and controlling members each adapted to cooperate directly with flexible feeding means and arranged on the receding side of the machine frame.

12. In a mining apparatus, a machine frame slideable on its bottom over the mine bottom during cutting and having at the rear end thereof a motor and at the forward end thereof cutting mechanism, and means for feeding and guiding said machine transversely of a face during cutting including a plurality of independently rotatable feed operating and controlling members each adapted to cooperate directly with flexible feeding means and rotating on parallel stationary axes on the same side of the machine frame.

13. In a mining apparatus, a machine frame carrying pivotally mounted kerf cutting mechanism swingable horizontally to cut a horizontal kerf in a mine wall and actuating means for said cutting mechanism, and self-contained means for swinging said cutting mechanism including a flexible connection attachment member coaxial with the pivot thereof, a plurality of selectively operable flexible member winding elements rotating on aligned axes parallel to the axis of cutting mechanism swing, and flexible connections therefrom to said attachment member.

14. In a mining apparatus, a machine frame slideable on a mine bottom and carrying pivotally mounted horizontally swinging kerf cutting mechanism swingable horizontally to cut a horizontal kerf in a mine wall and actuating means for said cutting mechanism, and self-contained means for swinging said cutting mechanism including a flexible connection attachment member coaxial with the pivot thereof, a plurality of selectively operable flexible member winding elements arranged in juxtaposition on the same side of the machine frame, and flexible connections coopearing directly with said winding elements and extending therefrom to said attachment member.

15. In a mining apparatus, a machine frame carrying pivotally mounted horizontally swinging kerf cutting mechanism swingable horizontally to cut a horizontal kerf in a mine wall and actuating means for said cutting mechanism, and means for swinging said cutting mechanism including a sheave coaxial with the pivot thereof, a plurality of selectively operable flexible member winding elements rotating on vertical axes, and flexible connections therefrom to said sheave.

16. In a mining apparatus, a machine frame slideable on a mine bottom and carrying pivotally mounted kerf cutting mechanism

swingable horizontally to cut a horizontal kerf in a mine wall and actuating means for said cutting mechanism, and means for swinging said cutting mechanism including a sheave coaxial with the pivot thereof, a plurality of selectively operable flexible member winding elements arranged on axes lying in longitudinal extending vertical planes, and flexible connections therefrom to said sheave.

17. In a mining apparatus, a machine frame slideable on a mine bottom and carrying pivotally mounted kerf cutting mechanism swingable horizontally to cut a horizontal kerf in a mine wall and actuating means for said cutting mechanism, and means for swinging said cutting mechanism including a sheave coaxial with the pivot thereof, a plurality of selectively operable flexible member winding elements arranged in juxtaposition at one side of the machine frame and rotating on axes parallel to the same straight line, and flexible connections therefrom to said sheave.

18. In a mining apparatus, a machine frame carrying pivotally mounted kerf cutting mechanism swingable horizontally to cut a horizontal kerf in a mine wall and actuating means for said cutting mechanism, and means for swinging said cutting mechanism including a sheave coaxial with the pivot thereof, a plurality of selectively operable flexible member winding elements rotating on axes parallel to the axis of cutting mechanism swing, and flexible connections therefrom to said sheave.

19. In a mining apparatus, a machine frame carrying pivotally mounted horizontally swinging cutting mechanism and actuating means therefor, and means for swinging said cutting mechanism including a sheave coaxial with the pivot thereof, a plurality of selectively operable flexible member winding elements rotating on aligned vertical axes, and flexible connections therefrom to said sheave.

20. In a mining apparatus, a machine frame slideable upon a mine bottom during cutting, cutting mechanism carried thereby including a pivoted cutter bar, bar swinging means operative to swing said bar in opposite directions, means for locking said bar in fixed relation to the frame, means operable independently of said bar swinging means for feeding said machine over the bottom during cutting, and a motor carried at the rear end of said frame and having at the front end thereof connections to said swinging and feeding mechanisms.

21. In a mining apparatus, a machine frame slideable upon a mine bottom during cutting, cutting mechanism carried thereby including a pivoted cutter bar, bar swinging means operative to swing said bar in opposite directions, means for locking said bar in fixed relation to the frame, means operable independently of said bar swinging

means for feeding said machine over the bottom during cutting, and a motor carried at the rear end of said frame and having at the front end thereof connections to said swinging and feeding mechanisms and to actuate said cutting mechanism.

22. In a mining apparatus, a machine frame slideable upon a mine bottom during cutting, cutting mechanism carried thereby including a pivoted cutter bar, bar swinging means operative to swing the bar in opposite directions, means for locking said bar in fixed relation to the frame, means operable independently of said bar swinging means for feeding said machine over the bottom during cutting, and a motor carried at the rear end of said frame and having at the front end thereof connections to said swinging and feeding mechanisms including common reduction gearing.

23. In a mining apparatus, a machine frame slideable upon a mine bottom during cutting, cutting mechanism carried thereby including a pivoted cutter bar, bar swinging means, means for locking said bar in fixed relation to the frame, means operable independently of said bar swinging means for feeding said machine over the bottom during cutting, and a motor carried at the rear end of said frame and having at the front end thereof connections to said swinging and feeding mechanisms including common plural speed reduction gearing.

24. In a mining apparatus, a machine frame slideable upon a mine bottom during cutting, cutting mechanism carried thereby including a pivoted cutter bar, bar swinging means, means for locking said bar in fixed relation to the frame, means operable independently of said bar swinging means for feeding said machine over the bottom during cutting, and a motor carried at the rear end of said frame and having at the front end thereof connections to said swinging and feeding mechanism including common plural speed reduction gearing all of whose elements rotate on horizontal axes.

25. In a mining apparatus, a machine frame slideable over a mine bottom during cutting, cutting mechanism carried thereby including a pivoted cutter bar, bar swinging means, means for locking said bar in fixed relation to the frame, means for feeding said machine over the bottom during cutting, and a motor having at the front end thereof connections to said swinging and feeding mechanisms including common plural speed reduction gearing all of whose elements rotate on transverse axes.

26. In a mining apparatus, a machine frame, cutting mechanism thereon, and means for effecting movement of said cutting mechanism during cutting comprising a plurality of relatively rotatable feed operating members each adapted to cooperate directly with

flexible feeding means and rotating on alined vertical axes at like peripheral speeds.

27. In a mining apparatus, a machine frame, cutting mechanism thereon, and means for effecting movement of said cutting mechanism during cutting comprising a plurality of feed operating members each adapted to cooperate directly with flexible feeding means and rotating on alined vertical axes and means for selectively transmitting power thereto to effect independent drive thereof at like peripheral speeds.

28. In a mining apparatus, a machine frame, swinging cutting mechanism pivotally mounted thereon, and means for effecting swinging movement of said cutting mechanism during cutting comprising a plurality of feed operating members each adapted to cooperate directly with flexible feeding means and rotating on alined vertical axes and means for selectively transmitting power thereto including friction clutches coaxial therewith.

29. In a mining apparatus, a machine frame, swinging cutting mechanism pivotally mounted thereon, and means for effecting swinging movement of said cutting mechanism during cutting comprising a plurality of feed operating members each adapted to cooperate directly with flexible feeding means and rotating on alined vertical axes and means for selectively transmitting power thereto including friction clutch means having a vertical axis.

30. In a mining apparatus, a machine frame, cutting mechanism thereon, and means for effecting movement of said cutting mechanism during cutting comprising a plurality of feed operating members each adapted to cooperate directly with flexible feeding means and rotating on alined vertical axes and means for selectively transmitting power thereto including friction clutches coaxial therewith and loading means therefor including an operating element extending through said members.

31. In a mining apparatus, a machine frame, cutting mechanism pivotally mounted thereon, a sheave coaxial with said pivot and fixed as to relative movement with respect to said cutting mechanism, a drum rotating on an axis parallel to said pivot and in the same plane perpendicular to said pivot with said sheave, a second drum rotating on an axis parallel to said pivot but in a different horizontal plane, flexible means passing from said first drums to said sheave and from said sheave to said second drum, and guide sheaves guiding said flexible means between said first mentioned sheave and said second drum.

32. In a mining apparatus, a supporting frame, a plurality of converging cutter bars pivotally mounted on said frame in superposed relation, each of said bars comprising

an elongated frame and provided with orbitally moving cutting elements arranged to cut a kerf to admit the bar, and means for simultaneously swinging said bars relative to said frame.

33. In a mining apparatus, a supporting frame, a plurality of converging cutter bars pivotally mounted on said frame in superposed relation, each of said bars comprising an elongated frame and provided with orbitally moving cutting elements arranged to cut a kerf to admit the bar, and means for simultaneously swinging said bars relative to said frame operative to effect swing in opposite directions.

34. In a mining apparatus, a supporting frame, a plurality of converging cutter bars pivotally mounted on said frame in superposed relation, each of said bars comprising an elongated frame and provided with orbitally moving cutting elements arranged to cut a kerf to admit the bar, and means for simultaneously swinging said bars relative to said frame operative to effect swing in opposite directions including independently operable feeding devices.

35. In a mining apparatus, a supporting frame, a cutter bar pivotally mounted thereon, and means for swinging said bar relative to said frame including a plurality of independently operable operating elements rotatable on vertical axes and flexible means cooperating directly with said elements and connectable to said bar.

36. In a mining apparatus, cutting mechanism comprising a cutter chain driving sprocket, a cutter bar having a portion in a plane perpendicular to the axis of rotation of said sprocket and including the pitch circle of said sprocket and another portion deviating from such plane, said portions cooperating to provide a continuous track for a cutter chain, each of said portions being presentable to the coal to effect cutting therewith, and a cutter chain driven by said sprocket and guided by said track comprising bit carrying links and universal connections therebetween.

37. In a mining apparatus, a cutter bar having angularly disposed plane portions each presentable to the coal and along each of which cutting is adapted to take place and provided with a circulating cutting element carrying cutter chain comprising cutter bit carrying links, and means providing universal connections between said links.

38. In a mining apparatus, a plurality of relatively converging pivoted cutter bars provided with relatively movable cutting elements, and direct driving means for said cutting elements rotating on axes in the same straight line.

39. In a mining apparatus, a plurality of converging pivoted cutter bars provided with circulating cutter chains, and driving

sprockets for said chains rotating on axes parallel to the same straight line, said bars being more remote at points adjacent their pivots than at their opposite ends.

40. In a mining apparatus, a plurality of converging pivoted cutter bars provided with circulating cutter chains, and driving sprockets for said chains rotating on aligned axes, said bars being more remote at points adjacent their pivots than at their opposite ends.

41. In a mining apparatus, a plurality of converging pivoted cutter bars provided with circulating cutter chains, and driving sprockets for said chains rotating on axes parallel to the same straight line, and perpendicular to the plane of one of said bars, said bars being more remote at points adjacent their pivots than at their opposite ends.

42. In a mining apparatus, a plurality of converging pivoted cutter bars provided with circulating cutter chains, and driving sprockets for said chains rotating on aligned axes perpendicular to the plane of one of said bars, said bars being more remote at points adjacent their pivots than at their opposite ends.

43. In a mining machine, in combination, a machine frame slidable on its bottom over a mine bottom during cutting and carrying a motor, cutting mechanism, a plurality of relatively rotatable members adapted to cooperate directly with flexible feeding means to effect machine feeding and guiding, a shaft extending longitudinally of the machine and carrying spaced elements constituting actuating means for said cutting mechanism and said last mentioned members, and power transmission mechanism between said elements and said members and mechanism respectively, the former transmission mechanism including a plural speed gearing whose elements rotate at all times on parallel stationary axes in advance of the motor.

44. In a mining apparatus, a machine frame slidable on its bottom on the mine bottom during cutting and having at the rear end thereof a motor and at the forward end thereof cutting mechanism and means for feeding and guiding said machine transversely of a face during cutting including a plurality of independently rotatable feed operating and controlling members each adapted to cooperate directly with flexible feeding means and rotatable on stationary axes on the same side of the machine frame, and means for positively driving either of the same independently of the other.

45. In a mining apparatus, a machine frame slidable on its bottom on the mine bottom during cutting and having at the rear end thereof a motor and at the forward end thereof cutting mechanism and means for feeding and guiding said machine trans-

versely of a face during cutting including a plurality of independently rotatable feed operating and controlling members each adapted to cooperate directly with flexible feeding means and on the receding side of the machine frame, and means for positively driving either of the same independently of the other.

46. In a mining apparatus, a machine frame, cutting mechanism thereon, and means for effecting movement of said cutting mechanism during cutting comprising a plurality of relatively rotatable feed operating members rotating on aligned vertical axes and each adapted to cooperate directly with a flexible feeding element, and a driving element therefor coaxial therewith and between the same.

47. In a mining apparatus, a machine frame, swinging cutting mechanism pivoted thereon, and means for effecting swinging movement of said cutting mechanism during cutting comprising a plurality of relatively rotatable feed operating members rotating on aligned vertical axes and each adapted to cooperate directly with a flexible feeding element.

48. In a mining apparatus, cutting mechanism including a plurality of converging relatively inclined cutter bars each carrying a cutter chain and cooperating to form a polygonal central core opening extending therethrough and adapted to cut out a wedge-shaped core from the coal face thereby forming a wedge-shaped kerf.

49. In a mining apparatus, cutting mechanism for cutting a wedge-shaped kerf in the coal face including a plurality of converging relatively inclined plane cutter bars provided with orbitally movable cutter chains supported on their margins.

50. In a mining apparatus, a machine frame, and cutting mechanism pivotally mounted thereon for cutting a wedge-shaped kerf in the coal face including a plurality of converging relatively inclined cutter bars and a cutter chain movably mounted on each of said bars.

51. In a mining apparatus, cutting mechanism including a substantially horizontal plane cutter bar, and a cooperating cutter bar having a horizontal portion parallel with said other cutter bar and a downwardly extending bent portion converging with said other cutter bar, said bars each carrying a cutter chain and cooperating to form a core passage and adapted to cut out a core from the coal face.

52. In a mining apparatus, a machine frame, cutting mechanism thereon including a pivoted cutter, and means for effecting swinging movement of said cutter in opposite directions relative to said frame including a plurality of relatively rotatable feed operating members and a cooperating flexible element having its intermediate portion con-

nected to said cutter and its end portions directly engaging said feed operating member respectively.

53. In a mining apparatus, a machine frame, cutting mechanism thereon including a pivoted cutter, and means for effecting swinging movement of said cutter in opposite direction including a plurality of relatively rotatable feed operating members and a cooperating flexible feeding element having its ends connected directly to said feed operating members and a intermediate portion engaging said cutter.

54. In a mining apparatus, a machine frame, cutting mechanism thereon, and means for effecting movement of said cutting mechanism during cutting comprising a plurality of relatively rotatable feed operating members rotating on aligned axes at like peripheral speeds and a flexible element cooperating directly with said feed operating members and attached to said cutting mechanism.

55. In a mining apparatus, a machine frame, swinging cutting mechanism pivoted thereon, and means for effecting swinging movement of said cutting mechanism during cutting comprising a plurality of relatively rotatable feed operating members rotating on aligned axes and flexible feeding means connected to said cutting mechanism and cooperating directly with said feed operating members.

56. In a mining apparatus, a machine frame slidable on its bottom directly on the mine bottom, cutting mechanism carried by said frame comprising a substantially V-shaped cutter device having a central core opening and orbitally movable circulating core cutting elements disposed along the forward and receding edges of said cutter device for cutting a substantially V-shaped full depth kerf disposed transversely of the coal face at the base of the mine wall, said cutter device extending lengthwise of the machine during the transverse cutting operation, and means for feeding and guiding the machine during the transverse cutting operation including a feed operating member and flexible feeding means cooperating directly therewith and including advance and receding flexible feeding portions.

57. In a mining apparatus, a machine frame slidable on its bottom directly on the mine bottom, cutting mechanism carried by said frame comprising a substantially V-shaped cutter device having a central core opening for cutting a substantially V-shaped full depth kerf disposed transversely of the coal face at the base of the mine wall, said cutter device extending lengthwise of the machine during the transverse cutting operation, and means for feeding and guiding the machine during the transverse cutting operation including relatively rotatable feed op-

- erating and controlling members, and flexible feeding means cooperating directly therewith and including advance and receding flexible feeding portions.
58. In a mining apparatus, a machine frame slidable on its bottom directly on the mine bottom, cutting mechanism carried by said frame comprising a substantially V-shaped pivoted cutter device having a central core opening for cutting a substantially V-shaped full depth kerf disposed transversely of the coal face at the base of the mine wall, said pivoted cutter device extending lengthwise of the machine during the transverse cutting operation, and means for feeding and guiding the machine during the transverse cutting operation and for swinging said pivoted cutter device relative to said frame including a relatively rotatable feed operating and controlling members and flexible feeding means cooperating directly therewith and including advance and receding flexible feeding portions.
59. In a mining apparatus, the combination with a support element and a horizontal kerf cutting element movably mounted thereon for movement horizontally relative thereto to cut a horizontal kerf in a mine wall, of feeding mechanism including flexible draft means having end portions attached to one of said elements, and means to tension different sections of said draft means to move said cutting element selectively in different directions relative to said support element, said tensioning means including a tensioning element cooperating directly with said flexible draft means and rotating on an axis lying in a longitudinally extending vertical plane.
60. In a mining apparatus, the combination with a support and a horizontal kerf cutter movably mounted thereon for movement horizontally relative thereto to cut a horizontal kerf in a mine wall, of feeding mechanism including flexible draft means, and means including winding devices arranged wholly at one side of said support for tensioning different sections of said draft means to move said kerf cutter selectively in different directions relative to said support when the latter is stationary, said draft means comprising a flexible cable section with which said winding devices cooperate.
61. In a mining apparatus, the combination with a support and horizontal kerf cutting devices movably mounted thereon for movement horizontally relative thereto to cut a horizontal kerf in a mine wall, of feeding mechanism including flexible draft means and means including winding devices arranged on a vertical axis for tensioning different sections of said draft means to move said cutting devices selectively in different directions relative to said support, said draft means comprising a single cable section having its end portions attachable to certain of said devices and its in-

termediate portion attachable to said other devices.

62. In a mining apparatus, the combination with a support and horizontal kerf cutting devices movably mounted thereon for movement horizontally relative thereto to cut a horizontal kerf in a mine wall, of feeding mechanism including flexible draft means and means including winding devices arranged on a vertical axis for tensioning different sections of said draft means to move said cutting devices selectively in different directions relative to said support, said draft means comprising a single cable section having its end portions attachable to certain of said devices and its intermediate portion attachable to said other devices, and means for operating said winding devices to vary the relative position thereof with respect to said attached portion of said cable section.

63. In a mining apparatus, the combination with a support element and a horizontal kerf cutting element movably mounted thereon for movement horizontally relative thereto to cut a horizontal kerf in a mine wall, of feeding mechanism including flexible draft means and means including winding devices rotating on a axis lying in a longitudinally extending vertical plane for tensioning different sections of said draft means to move said cutting element selectively in different directions relative to the support element, said draft means comprising a single cable section having portions thereof attached to said winding devices and one of said elements respectively.

64. In a mining apparatus, the combination with a support element and a horizontal kerf cutting element movably mounted thereon for movement horizontally relative thereto to cut a horizontal kerf in a mine wall, of feeding mechanism including flexible draft means and means to tension different sections of said draft means to move said cutting element selectively in different directions relative to said support element, said mechanism including winding devices carried by one of said elements and arranged on a vertical axis and a cooperating cable section attached to said other element.

65. In a mining apparatus, the combination with a support element and a horizontal kerf cutting element pivotally mounted thereon to swing horizontally relative thereto to cut a horizontal kerf in a mine wall, of feeding mechanism including flexible draft means and means to tension different sections of said draft means to swing said cutting element about its pivot selectively in different directions relative to said support element, said mechanism including winding drum means carried by one of said elements and arranged with its axis extending in the same direction as the pivotal axis of said cutting element and a cooperating cable section attached to said

drum means and one of said elements respectively.

66. In a mining machine, a machine frame adapted to rest upon and slide in any direction over the mine bottom, a motor carried thereby, cutting mechanism driven by said motor including a pivoted cutter bar, feeding means driven by said motor for propelling the machine bodily over the mine bottom during cutting, and mechanism driven by said motor wholly independently of said machine feeding means for swinging said cutter bar about its pivot.

67. In a mining machine, a machine frame adapted to rest upon and slide in any direction over the mine bottom, a motor carried thereby, cutting mechanism driven by said motor including a pivoted cutter bar, feeding means driven by said motor for propelling the machine bodily over the mine bottom during cutting, and mechanism driven by said motor wholly independently of said machine feeding means for swinging said cutter bar about its pivot and operable at will as the machine is fed bodily relative to the coal face.

68. In a mining machine, a machine frame adapted to rest upon and slide in any direction over the mine bottom, a motor carried thereby, cutting mechanism driven by said motor including a pivoted cutter bar, feeding means driven by said motor for propelling the machine bodily over the mine bottom during cutting, and mechanism driven by said motor wholly independently of said machine feeding means for swinging said cutter bar about its pivot by power in opposite directions.

69. In a mining machine, a machine frame adapted to rest upon and slide in any direction over the mine bottom, a motor carried thereby, cutting mechanism driven by said motor including a pivoted cutter bar, feeding means driven by said motor for propelling the machine bodily over the mine bottom during cutting, and mechanism driven by said motor wholly independently of said machine feeding means for swinging said cutter bar about its pivot by power in opposite directions and operable at will as the machine is fed bodily relative to the coal face.

70. In a mining machine, a machine frame adapted to rest upon and slide in any direction over the mine bottom, a motor carried thereby, cutting mechanism driven by said motor including a cutter bar pivoted on said frame and having mounted thereon an endless cutter chain, feeding means driven by said motor for feeding the machine relative to the coal face including a feed operating member and a cooperating flexible element, and mechanism driven by said motor for swinging said cutter bar about its pivot wholly independently of said feed operating member and said flexible element and while

said cutter chain is disconnected from said motor.

71. In a mining machine, a machine frame adapted to rest upon and slide in any direction over the mine bottom, a motor carried thereby, cutting mechanism driven by said motor including a pivoted cutter bar, feeding means driven by said motor for propelling the machine bodily over the mine bottom during cutting including a feed operating member and a cooperating flexible element, and mechanism driven by said motor for swinging said cutter bar about its pivot by power wholly independently of said feed operating member and cooperating flexible element.

72. In a mining machine, a machine frame adapted to rest upon and slide in any direction over the mine bottom, a motor carried thereby, cutting mechanism driven by said motor including a pivoted cutter bar, feeding means driven by said motor for propelling the machine bodily over the mine bottom during cutting including a feed operating member and a cooperating flexible element, and mechanism driven by said motor for swinging said cutter bar about its pivot by power in opposite directions wholly independently of said feed operating member and cooperating flexible element.

73. In a mining machine, a machine frame adapted to rest upon and slide in any direction over the mine bottom, a motor carried thereby, cutting mechanism driven by said motor including a pivoted cutter bar, feeding means driven by said motor for propelling the machine bodily over the mine bottom during cutting, and mechanism driven by said motor wholly independently of said machine feeding means for swinging said cutter bar about its pivot by power in opposite directions while said feeding means operates continuously in the same direction.

74. In a mining machine, a machine frame adapted to rest upon and slide in any direction over the mine bottom, a motor carried thereby, cutting mechanism driven by said motor including a pivoted cutter bar, feeding means driven by said motor for propelling the machine bodily over the mine bottom during cutting, and mechanism driven by said motor wholly independently of said machine feeding means for swinging said cutter bar about its pivot by power in opposite directions while said feeding means operates continuously in the same direction and operable at will as the machine is fed bodily relative to the coal face.

75. In a mining machine, a machine frame adapted to rest upon and slide in any direction over the mine bottom, a motor carried by said frame, cutting mechanism driven by said motor including a pivoted cutter bar swingable horizontally relative to said frame, feeding and guiding means driven

by said motor for feeding the machine bodily laterally over the mine bottom in a direction substantially perpendicular to the longitudinal axis of the machine and for guiding the machine during said lateral movement and including flexible feeding elements extending in opposite directions from the opposite ends of said frame and connectible at their free ends to extraneous abutments, and mechanism driven by said motor and operated wholly independently of said flexible feeding elements for swinging said cutter bar about its pivot relative to said frame.

76. In a mining machine, a machine frame adapted to rest upon and slide in any direction over the mine bottom, a motor carried by said frame, cutting mechanism driven by said motor including a pivoted cutter bar swingable horizontally relative to said frame, feeding and guiding means driven by said motor for feeding the machine bodily laterally over the mine bottom in a direction substantially perpendicular to the longitudinal axis of the machine and for guiding the machine during said lateral movement and including flexible feeding elements extending in opposite directions from the opposite ends of said frame and connectible at their free ends to extraneous abutments, and mechanism driven by said motor and operated wholly independently of said flexible feeding elements for swinging said cutter bar about its pivot relative to said frame and operable at will as the machine is fed bodily laterally relative to the coal face.

77. In a mining machine, a machine frame adapted to rest upon and slide in any direction over the mine bottom, a motor carried by said frame, cutting mechanism driven by said motor including a pivoted cutter bar swingable horizontally relative to said frame, feeding and guiding means driven by said motor for feeding the machine bodily laterally over the mine bottom in a direction substantially perpendicular to the longitudinal axis of the machine and for guiding the machine during said lateral movement and including flexible feeding elements extending in opposite directions from the opposite ends of said frame and connectible at their free ends to extraneous abutments, and mechanism driven by said motor and operated wholly independently of said flexible feeding elements for swinging said cutter bar about its pivot relative to said frame and operable at will as the machine is fed bodily laterally relative to the coal face.

78. In a mining machine, a machine frame adapted to rest upon and slide in any direction over the mine bottom, a motor carried by said frame, cutting mechanism driven by said motor including a pivoted cutter bar swingable horizontally relative to said frame, feeding and guiding means driven by said motor for feeding the machine bodily later-

ally over the mine bottom in a direction substantially perpendicular to the longitudinal axis of the machine and for guiding the machine during said lateral movement and including flexible feeding elements extending in opposite directions from the opposite ends of said frame and connectible at their free ends to extraneous abutments, and mechanism driven by said motor and operated wholly independently of said flexible feeding elements for swinging said cutter bar about its pivot by power in opposite directions while said feeding means operates continuously in the same direction and operable at will as the machine is fed bodily laterally relative to the coal face.

79. In a mining machine, a machine frame adapted to rest upon and slide in any direction over the mine bottom, a motor carried by said frame, cutting mechanism driven by said motor including a pivoted cutter bar swingable horizontally relative to said frame, feeding and guiding means driven by said motor for feeding the machine bodily laterally over the mine bottom in a direction substantially perpendicular to the longitudinal axis of the machine and for guiding the machine during said lateral movement and including relatively rotatable power operated and controlled feed operating members mounted on said frame and flexible feeding elements cooperating respectively with said feed operating members and extending in opposite directions from the opposite ends of said frame and connectible at their free ends to extraneous abutments, and mechanism driven by said motor and operated wholly independently of said flexible feeding elements for swinging said cutter bar about its pivot relative to said frame.

In testimony whereof I affix my signature.

FRANK CARTLIDGE.
